(57) **CLAIM**

The ornamental design for a flexible container for mixing and administering drugs and feeds, as shown and described.

DESCRIPTION

FIG. 1 is a perspective view of a flexible container for mixing and administering drugs and feeds according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a flexible container for mixing and administering drugs and feeds according to a second embodiment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines illustrate portions of the flexible container for mixing and administering drugs and feeds that form no part of the claimed design.

The oblique line shading on the front of the flexible container for mixing and administering drugs and feeds in FIGS. 1, 2, 4-9 and 11-14 represents a transparent material.

The oblique line shading on the rear of the flexible container for mixing and administering drugs and feeds in FIGS. 3-7 and 10-14 represents an opaque, light-reflective, and metallic foil material.

(Continued)

The second embodiment of the flexible container for mixing and administering drugs and feeds is shown with a symbolic break between boundary lines in FIGS. 8-12. The boundary lines form no part of the claimed design. The appearance of any portion of the flexible container for mixing and administering drugs and feeds between the boundary lines also forms no part of the claimed design.
